UNITED STATES PATENT OFFICE.

MARTIN HARDSCOG, OF OTTUMWA, IOWA.

MINER'S PICK.

SPECIFICATION forming part of Letters Patent No. 759,704, dated May 10, 1904.

Application filed May 2, 1903. Serial No. 155,314. (No model.)

To all whom it may concern:

Be it known that I, MARTIN HARDSCOG, a citizen of the United States of America, and a resident of Ottumwa, Wapello county, Iowa, have invented a new and useful Miner's Pick, of which the following is a specification.

The object of this invention is to provide means for removably and replaceably connecting a miner's pick to a handle, stem, or shank.

10 My invention consists in the construction, arrangement, and combination of elements hereinafter set forth, pointed out in my claims, and illustrated by the accompanying drawings, in which—

15 Figure 1 is an elevation of the completed device. Fig. 2 is a view, partly in section, illustrating the construction of the means employed to connect the stem and pick. Fig. 3 is a sectional view on the indicated line 3-3 of

20 Fig. 1. Fig. 4 is a perspective of the eccentric lock detached from the other parts.

In the construction of the device as shown the numeral 10 designates a stem, haft, shank, or socket, which is formed with a recess 11 longitudinally of one end portion for the reception of a handle 12, the latter preferably made of wood. The rear end portion of the stem containing the recess 11 preferably is oval in cross-section, and the forward portion

30 of said stem preferably is relatively broad and flat and formed with a transverse recess or eye 13, extending from side to side thereof and of a size to admit a pick 14, hereinafter described.

35 The pick 14 may be any of the conventional forms, preferably rectangular in cross-section and tapering from a rectangular central portion to points at either end. On one side and at its central portion 15 the pick 14 is ser-

40 rated or roughened, and a corresponding serrated or roughened surface 16 is formed on the inner face of the outer end portion of the stem 10. Holes 17 are formed in the stem 10 and communicate with the recess 13 therein,

45 and a circular lock 18 is mounted eccentrically for rotary adjustment in said holes, the body of said lock contained in the rear portion of the recess. The lock 18 is formed with a central axial aperture 19, square or other-

wise angular in cross-section. Holes 20 are 50 formed in the stem 10, and holes 21 are formed in the lock 18 and arranged for registration at times with the holes 20 for the reception of a key, nail, pin, or similar device for holding the lock stationary relative to the stem. When 55 the lock is turned into the position shown by dotted lines in Fig. 2, the pick 14 is inserted and seated in the recess 13 by endwise movement and the roughened portion 15 of the pick is brought into position opposite the serrated 60 face 16 of the end portion of the stem. Then the lock 18 is rotated, preferably by the insertion therein of the point of another pick, into the position shown by solid lines in Fig. 2, thus causing the periphery of the lock to 65 engage the pick 14 and seat the same firmly in the recess. Then the pick may be employed for any desired purpose and the eccentrically-positioned lock will hold and firmly seat the tool 14 in the stem. 70

The parts being subject to wear and at times to severe strain, it may occur that the pick 14 will become loose in the stem by the accidental rotation of the eccentrically-mounted lock, and to obviate such difficulty I have provided 75 the pin-holes 20 and 21 and the pin 22, which pin may be an ordinary nail or peg of wood or other material of inconsiderable cost.

The tool 14 may be removed from the stem by endwise movement upon a reverse movement of the lock 18 into the position shown by dotted lines in Fig. 2, such reverse movement also being accomplished, preferably, by the use of the point of a pick in the angular aperture 19 of the lock. 85

I claim as my invention—

1. The eyeless miner's pick, comprising the stem formed with a recess, a pick-blade mounted in the recess, and an eccentrically-mounted lock wholly in the recess and arranged for 90 rotation into engagement with the pick-blade at times.

2. The eyeless miner's pick, comprising the stem formed with a recess, a pick-blade removable and replaceable in said recess by endwise movement, a lock mounted eccentrically for rotary adjustment in said stem and arranged for engagement with said pick-blade 95

at times, said lock formed with an angular axial aperture to receive a rotating means, and a handle attached to said stem.

3. The eyeless miner's pick, comprising the 5 stem, the handle attached thereto, the pick-blade removably and replaceably mounted in the stem and the eccentrically-mounted lock and trunnions thereon journaled in said stem said lock arranged for engagement with the 10 pick-blade.

4. The eyeless miner's pick, comprising the 15 stem, the handle attached to said stem, the pick-blade removably and replaceably mounted in said stem, the eccentrically-mounted lock in said stem and arranged to engage said pick-blade at times, and means for securing 20 said lock against rotary movement in said stem.

5. The eyeless miner's pick, comprising the 25 stem formed with a transverse recess, the inner surface of one wall of said recess serrated, the pick-blade formed with a roughened surface mating the serrated surface of the stem

and mounted in said transverse recess of the 25 stem, and the eccentrically-mounted lock and trunnions thereon journaled in said stem, said lock formed with an angular axial aperture arranged for engagement with said pick-blade at times, whereby the roughened surface of the pick-blade is brought into interlocking 30 engagement with the serrated portion of the stem.

6. The miner's pick, comprising the stem formed with a recess and apertures opening to and on opposite sides of said recess, a pick 35 mounted through said recess, a circular lock in said recess and eccentric trunnions on said lock and journaled in the stem, and means for locking said lock against rotation.

Signed by me at Ottumwa, Iowa, this 28th 40 day of February, 1903.

MARTIN HARDSCOG.
